(57) **CLAIM**

The ornamental design for a patient-support frame, as shown and described.

DESCRIPTION

FIG. 1 is a top-isometric view of a patient-support frame showing my new design

FIG. 2 is a top view thereof.

FIG. 3 is a longitudinal-side view thereof.

FIG. 4 is a horizontal-side view thereof; and,

FIG. 5 is a bottom view thereof.

The broken lines are included for the purpose of illustrating portions of the patient-support frame that form no part of the claimed design.
